HEATING SYSTEM

Emil Blanckenburg, San Francisco, Calif., assignor to Petroleum Conversion Corporation, New York, N. Y., a corporation of Delaware

Application October 17, 1930, Serial No. 489,284

5 Claims. (Cl. 196—66)

My present invention relates to improvements in systems of heating which comprise a plurality of heaters of the regenerative type, particularly those commonly designated hot blast stoves.

5 The system of heating to which my invention relates is one which is adapted to supply heated combustible gas for use in the cracking of hydrocarbon oils in which the heated gas is relied upon to accomplish the cracking of the hydrocarbon material with which it is mingled. The source of such gas is commonly the cracking system itself since such gas is produced in the cracking operation and contains hydrogen, methane and other hydrocarbons and some carbon

10 monoxide and may have a fuel value of around 600 B. t. u. per cubic foot. Usually it is also used as fuel for the stoves. The heating of this gas and its combustion give rise to problems which do not occur when the blast stoves are used for heating air, as in the blast furnace industry.

15 In the first place, unless proper precautions are taken, the introduction of air into the stove for commencing the firing period following the heat yielding or so-called blast period, may result 20 in serious explosion by reason of the presence of combustible gas in the stove; in the second place, the combustion of so rich a gas as distinguished from the low calorific blast furnace gas presents the difficulty that the combustion temperatures produced are too high.

25 I have undertaken to solve these difficulties while employing a plurality of stoves as a unit, by using the combustion gases delivered from a stove being heated both for the purpose of diluting the high calorific gas used for combustion, and as a purge for the stoves both preceding and following the blast period. My invention is best understood by reference to the following detailed description taken with the annexed drawing in 30 which:

Figure 1 is a view in vertical section of a blast furnace and stack containing an illustrative embodiment of the invention; and

35 Figure 2 is a plan view of a battery of three of such units.

40 Referring to Figure 1, 10 denotes a regenerative heater of the blast furnace type of standard construction, which is provided with a burner 13, a vertically extended combustion chamber 15 and checker-work 17 providing downwardly extending vertical flues, as shown. Communicating with said flues is a collecting flue 19 which has therein a chimney valve 21 and communicates with a stack 23 by means of duct 25. Duct 25 has therein a slide valve 27 while

stack 23 has a valve or damper 29. For the purpose of recovering heat in the flue gases, I preferably provide an air heater or recuperator 31 which is connected with the stack by means of a pipe 33. Accordingly, by means of the 60 damper 29 or valve 27, the proportion of flue gases passing through the air heater may be varied as desired. Air under the requisite pressure for combustion is admitted to the air heater thru a conduit indicated at 36, passes through 65 the heater and out thru a duct 37 shown in dotted lines and thence to burner 13. Gas to be burned is supplied from a main 39 to burner 13 thru a connecting pipe 41.

For the purpose of employing a portion of the 70 spent flue gases in any combustion space, the ducts 25 of the stoves are joined by connecting pipe 42 by means of short lengths of pipe 43, each having therein a valve 44. Pipe 42 is connected with a cross pipe 45 and this in turn is 75 joined to a distributor pipe 49 which connects each stove by means preferably of both a pipe 51 having therein a valve 53 leading directly to the combustion space of each stove 10 and also a valved branch pipe 52 leading to burner 13. 80 By this means of this supply of flue gas to the burner, the combustion temperature occurring therein is suitably reduced. In order to provide for circulating the gas as required, a motor driven fan 54 is provided at the inlet of pipe 85 45. For conducting the purge directly to the stack when this is desired a by-pass 57 is provided, having a valve 58 and leading from outlet 19 to pipe 33.

In the operation of the system it will be understood that a given stove of the system is first brought up to temperature by firing with gas from the main 39 during which operation air is supplied through duct 37 which has been preheated in heater 31. Also a portion of the 90 flue gases from duct 25 is recirculated by means of fan 54, conduit 45 and connection 52 to burner 13 and connections 51 to combustion space 15. Since the firing period is longer than the blast 95 ing period, two stoves of the three shown will be heated simultaneously, for a considerable part of the firing period of each and up to 50% or more of the flue gases will be drawn from the stacks of the stoves on fire and returned through manifold 45 to the combustion zone or the burner for diluting the high B. t. u. fuel gas. When a stove has reached the proper temperature, the combustion is stopped by shutting off the gas through pipe 41 and the air through duct 37 by means of a valve 38. The next step is to 100 105 110

insure that no excess of air is present in the stove, and accordingly the stove is purged by continuing the admission of flue gases from manifold 49 either through the burner 13 or 5 through a side connection 53 for a brief period after the air is shut off. The course of the purging gas is through the stove and then out through the stove and then out through by-pass pipe 57, valve 58 and pipe 33 to the stack. When 10 the stove has been thus freed of air, the gas to be heated, which may be termed the heat-carrier gas, is admitted through valve 56 from the cold blast main 55 and allowed to bring the stove up to the pressure prevailing in the oil 15 cracking system. As shown, cold blast main 55 has branches 55'. The latter, which have valves 56 therein, are joined to the stoves through pipe 19. The blast period is now begun by passing the cold gas through the stove and conducting 20 it therefrom to the cracking system through a so-called hot blast main (not shown) having connections 59 to each stove. The blast period is continued until the temperature in the stove has dropped below the desired minimum. When 25 this has occurred the supply of carrier gas is stopped and the pressure in the stove is reduced to atmospheric by bleeding off the carrier gas therein. When atmospheric pressure has been reached the stove is purged of the combustible 30 gas in a similar manner as purging for air, and for this purpose flue gas from the flue gas main 49 is admitted to connection 51, and also steam is admitted, the carrier gas and steam being displaced and lead through by-pass 57 to stack 23. 35 During this operation the chimney valve 21 is closed to prevent the inflammable carrier gas from entering flue 25 and valve 44, which would admit the gas to the fan 54, and thus mingle this gas with the flue gas from the other stoves. 40 If desired, by-pass 57 may communicate with a gas holder not shown for storing the carrier gas blown down from the stove to nearly atmospheric pressure.

In many instances it may be desired to use 45 a fuel other than the gas produced in the cracking system for heating the stoves. Where a fuel, particularly a gaseous fuel, is of low calorific value, the amount of flue gas returned to the combustion zone or to the burner for diluting the fuel gas will of course be less or may 50 be omitted entirely during the firing period. It may be advantageous to use natural gas having a calorific value of 1,000 B. t. u. or more, in which event the flame temperature would be 55 far in excess of the optimum and likely to damage the brickwork of the combustion chamber. It is desired then to greatly dilute the fuel gas with the recycle flue gas within the burner, together with the preheated air for combustion. 60 It may also be desirable to have available steam which may be used to supplement the flue gas used for purging and for this purpose a source of steam 60, Figure 1, preferably superheated, is provided. Many other changes may be made 65 in the method and apparatus described in detail without departing from the spirit of the invention or from the scope of the appended claims.

I claim:

1. In a system for supplying heated combustible gas suitable as an aid in the cracking of 70

hydrocarbon oils, the method of operating a plurality of hot blast stoves which consists in heating a given stove by burning fuel therein, and then, when the stove has reached the desired temperature, discontinuing the heat, and passing through the stove products of combustion from another stove which is being heated, whereby to purge same of air. 80

2. In a system for supplying heated combustible gas suitable as an aid in the cracking of 85 hydrocarbon oils, the method of operating a plurality of hot blast stoves, the steps which consist in first heating a given stove by burning fuel therein, then when the desired temperature is reached, beginning the blast period by passing combustible gas therethrough, continuing the blast until the stove has cooled off, discontinuing the flow of combustible gas and then purging the stove of said gas by passing through it flue gases from another stove on fire and leading the purge to a stack. 90

3. In an oil cracking system, an apparatus for heating a combustible gas, comprising a plurality of blast stoves, means for supplying same with a fuel for combustion therein, each of said 100 stoves communicating with a stack, a conduit for leading combustion gases from the stove to the stack communicating therewith, a second conduit for leading a portion of the produced flue gas to the combustion zone of said stove 105 and a separate pipe from the outlet of said stove to said stack, valves in said pipe and said conduits whereby, when the blasting period is completed, the flue gas from the system may traverse said stove for the purpose of purging 110 same of combustible gases and the purged gas pass through said pipe to the stack and not enter said conduit leading from said blast stove to the stack. 115

4. In a system for supplying heated combustible gas suitable as an aid in the cracking of 120 hydrocarbon oils, the method of operating a plurality of hot blast stoves comprising the steps which consist in heating a given stove by burning a fuel of comparatively high calorific value 125 while diluting the fuel as it is burned by combustion (flue) gas produced by the same or another stove in the series to thereby reduce the flame temperature, then when the stove has reached the desired temperature, discontinuing 130 the heating by cutting off the supply of fuel and air but continuing the admission of the flue gas until the stove is purged of free oxygen. 135

5. In the method according to the preceding claim, the further steps, when the said purging 140 operation has been accomplished, of leading a combustible gas through said stove to heat said gas until the temperature of the stove has dropped to a predetermined temperature, discontinuing the flow of the gas to be heated, leading off the excess combustible gas in the stove, then admitting a supply of flue gas from another stove in the series to purge the stove of combustible gas and conducting the mixture of flue and combustible gas from the stove by a separate 145 route from that of the gases of combustion produced in the stove whereby no combustion gas is mixed with the supply of flue gas which is circulated in the other stoves. 150

EMIL BLANCKENBURG. 145
